CLAIM

The ornamental design for a baseball shirt, as shown and described.

DESCRIPTION

FIG. 1 is a front view of a first embodiment, showing my new design;

FIG. 2 is a left view of the first embodiment thereof;

FIG. 3 is a back view of the first embodiment thereof;

FIG. 4 is a top view of the first embodiment thereof;

FIG. 5 is a front view of a second embodiment, showing my new design;

FIG. 6 is a left view of the second embodiment thereof;

FIG. 7 is a back view of the second embodiment thereof;

FIG. 8 is a top view of the second embodiment thereof;

FIG. 9 is a front view of a third embodiment, showing my new design;

FIG. 10 is a left view of the third embodiment thereof;

FIG. 11 is a back view of the third embodiment thereof;

FIG. 12 is a top view of the third embodiment thereof;

FIG. 13 is a front view of a fourth embodiment, showing my new design;

FIG. 14 is a left view of the fourth embodiment thereof;

FIG. 15 is a back view of the fourth embodiment thereof;

FIG. 16 is a top view of the fourth embodiment thereof;

FIG. 17 is a front view of a fifth embodiment, showing my new design;

FIG. 18 is a left view of the fifth embodiment thereof;

FIG. 19 is a back view of the fifth embodiment thereof;

FIG. 20 is a top view of the fifth embodiment thereof;

FIG. 21 is a front view of a sixth embodiment, showing my new design;

FIG. 22 is a left view of the sixth embodiment thereof;

FIG. 23 is a back view of the sixth embodiment thereof; and,

FIG. 24 is a top view of the sixth embodiment thereof.

Broken lines are used to show environment and unclaimed elements.
